(57) **CLAIM**

The ornamental design for a rocker pedestal, as shown and described.

DESCRIPTION

FIG. 1 is a front-top-right perspective view of a rocker pedestal, according to the present invention.

FIG. 2 is a front view of the rocker pedestal.

FIG. 3 is a rear view of the rocker pedestal.

FIG. 4 is a left side view of the rocker pedestal.

FIG. 5 is a right side view of the rocker pedestal.

FIG. 6 is a top view of the rocker pedestal; and,

FIG. 7 is a bottom view of the rocker pedestal.

The broken lines in FIG. 7 of the drawings show portions of the rocker pedestal that form no part of the claimed design.
